UNITED STATES PATENT OFFICE.

HENRY SCHWARTZ, OF CHICAGO, ILLINOIS.

METHOD OF FORMING BUSHING STRUCTURES.

Application filed December 10, 1927. Serial No. 239,207.

This invention relates to the method of forming a bushing structure and has special reference to the method for forming a bushing structure such as is employed particularly in the construction of metallic barrels and containers that are used for storing or shipping oils or other liquids or semi-liquids, the bushing structure being provided to receive a bung or stopper in a fluid-tight assembly. 5 More particularly this invention relates to a new and novel method of forming a bushing structure comprising forming a flange at the periphery of an aperture in a barrel or other container, then inserting a threaded aperture body portion into the flanged portion and finally in dove-tailing the flanged portion to secure the body portion rigidly and firmly in position. 10

In order to guard against the unauthorized opening of the barrel or container, this invention also relates to a method of forming a seal for the bung or stopper comprising bending a collar formed integrally with the beforementioned flange over a ring thereby holding the latter in an assembled relation with the bushing structure, the ring having a plurality of apertures therein to receive a sealing wire or string threaded through an aperture in a projection on a stopper or bung fitted into the bushing structure. 20

Further objects will hereinafter be referred to and for a better understanding of the nature, characteristics and scope of this invention, reference may be had to the accompanying drawings and the following description, in which drawings:

Figure 1 is a sectional view of a barrel head blank;

Fig. 2 is a sectional view of a punch and die mechanism showing a flange being formed on the blank of Fig. 1;

Fig. 3 is a sectional view of another punch and die mechanism showing the body portion of the bushing structure inserted in the flanged portion of the blank and in position to receive the dove-tailing or crimping action of the die;

Fig. 4 is a view similar to Fig. 3 showing a changed position of the punch and die members wherein the flange is dove-tailed or crimped to retain the main body portion of the bushing structure;

Fig. 5 is the final operation showing the collar of the flange member being bent over or crimped to receive a ring, the latter being an element of a sealing means; and

Fig. 6 is a vertical sectional view showing the completed bushing assembly.

Referring now to the drawings, a barrel head blank 10 is provided with an aperture 11 in any well known manner whereafter the blank is interposed between a punch 12 comprising an enlarged head 13 having a polygonally shaped portion 14 of a smaller diameter extending downwardly therefrom, 60 the polygonally shaped portion 14 having a preferably annular projection 15 formed thereon of a smaller diameter.

A die 16 is provided with an annular aperture at the lower portion thereof of a diameter greater than the diameter of the annular projection 15 by the thickness of the material of the barrel head blank 10. The upper portion of the die 16 is provided with a polygonally shaped aperture 18 of a diameter greater than the diameter of the polygonally shaped portion 14 of the die 12 by the thickness of the material of the blank 10. An annular recessed portion 19 is formed in the shoulder provided 70 at the junction of the enlarged head portion 13 and the polygonally shaped portion 14 to receive an annular ridge 20 formed on the upper surface of the die 16 adjacent the edge of the polygonally shaped aperture 18. 75

The punch and die members 12 and 16, respectively formed flanged portions on the barrel head from material surrounding the aperture 11. These flanged portions are of two different diameters, the flanged portion 80 of the larger diameter being of a polygonal contour and the flanged portion of the smaller diameter being preferably annular. Further, an annular beaded portion is formed on the supporting wall or blank 10 surrounding the polygonally shaped flanged portion for a definite purpose as will hereinafter be pointed out.

The barrel head is next placed on a die member preferably comprising a plurality of segments 21 pivotally mounted on a supporting structure 22, one segment being required for each side of the polygonally shaped flanged portion. The segment 21 preferably extends the full width of each 100 side of the flange and is held in an "up" position, as shown particularly in Fig. 3, by means of spring pressed plungers 23, the plungers extending through and being supported by the supporting structure 22. In order to limit the upward movement of the pivotally mounted segments 21, an adjust- 105

able screw member 24 is threaded in a vertically extending projection of the supporting member 22 to engage an offset portion in the segment 21. It will be apparent that by adjusting the screw members 24, the height of the free end of the segment 32 may be raised or lowered as desired.

The segment 21 is provided with a tapered engaging face 25 forming an acute angle 10 with the upper surface thereof. An internally threaded polygonally shaped body portion 25 is disposed in the socket formed by the shoulder at the junction of the annular flange and the polygonally shaped flange. 15 This socket is formed outwardly on the barrel head from the inner portion of the container. The opposite edges of the body portion 25, when viewed in cross section, converge inwardly toward the interior of 20 the barrel provided that the flange is comprised of an even number of sides. However, if an uneven number of sides is provided, any two sides when viewed together in cross section will converge inwardly, that 25 is, toward the interior of the barrel.

By referring now to Fig. 4 of the drawing, it will be seen that the segments 21 are moved inwardly by a punch member 26 whereby the segments 21 have been pivoted 30 to a position such that the diameter between the diametrically opposite upper edge portions of the engaging face 25 is smaller than the diameter between the corresponding upper edge portions of the engaging face 25 in 35 Fig. 3. By reason of the taper of the engaging face 25, the polygonally shaped flange is crimped inwardly against the inwardly converging edges of the body portion and the material of the beaded portion formed 40 on the blank 10 adjacent the polygonally shaped flange, is taken up so that the supporting wall 10 is flat. The main body portion is now held in a firm assembled relation in the polygonally shaped socket. 45 A ring 27, having apertures 38 formed therein, is inserted around the annular flange extending from the polygonally shaped socket and the barrel head 10 is then interposed between a punch member 29 and a 50 die member 30. The actuation of the punch and die members forms the annular flange over the ring 27 in order that the latter may have a fixed relation with the bushing structure. Although it has been stated herein- 55 before that the flange extending from the polygonally shaped socket is annular, it may be desirable to form this flange of a polygonal contour in which case the aperture 17 in the die member 16 and the projection 60 15 of the punch member 12 will be of a like contour.

By referring to Fig. 6, a completed bushing structure is shown wherein an internally threaded polygonally shaped body portion 65 is secured in a socket extending outwardly

from a barrel head. When this bushing structure is viewed in cross section, the outer edges thereof converge inwardly, that is, toward the interior of the barrel or container. The side walls of the socket are formed 70 against these inwardly converging edges of the main body portion and force the latter against a shoulder at the junction of the annular flange and these side walls. The annular flange holds the ring 27 in a secure 75 relation with the bushing structure. However, it may be desirable to dispense with the annular ring 27 whereafter the annular portion 15 of the punch 12 and the annular aperture 17 of the die 16 may be dispensed 80 with, thereby merely providing a shoulder formed integrally with the side walls of the socket.

While but a single embodiment of this invention is herein shown and described, it 85 is to be understood that various modifications will be apparent to those skilled in the art without departing from the spirit and scope of this invention and it is desired, therefore, that the same be limited only by 90 the scope of the prior art and the appended claims.

I claim:

1. The method of forming a bushing structure for metallic barrels and the like 95 consisting of cutting a hole in a supporting wall thereof, forming an outwardly extending socket from the material adjacent said hole and a beaded portion adjacent the wall of said socket, fitting an internally threaded 100 body portion in said socket, and thereafter forming the walls of said socket against inwardly converging edges of said body portion thus using up the material of said beaded portion. 105

2. A method of securing an annular internally threaded bushing in position with respect to an aperture in the sheet metal wall of a container, said bushing having its diameter adjacent its outer face greater than 110 its diameter adjacent the wall of the container, which method comprises forming a collar from the sheet metal wall about said aperture, said collar extending outwardly from said wall and having an annular flange for the outer face of the bushing to lie against and said collar having a diameter large enough to permit the insertion of the bushing into said collar from the inside side of said wall, inserting said bushing into said 115 collar from the inside side of the container wall to bring its outer face against said flange, and exerting pressure on said collar from the outside side of said wall to contract said collar to cause it to fit snugly 120 against said bushing. 125

3. A method of securing an annular internally threaded bushing in position with respect to an aperture in the sheet metal wall of a container, said bushing having its di- 130

diameter adjacent its outer face greater than its diameter adjacent the wall of the container, which method comprises making an opening in said wall, forming a collar surrounding said opening, said collar extending outwardly from said wall and having an annular flange for the outer face of the bushing to lie against said collar having a diameter large enough to permit insertion of the bushing into the collar from the inside side of said collar, forming an inwardly extending annular corrugation in said wall surrounding said collar, resulting in a bead on the inside side of said wall, inserting said bushing into said collar from the inside side of the container wall to bring its outer face against said flange and exerting pressure on said collar from the outside side of said collar to straighten out said annular corrugation and to contract said collar to cause it to fit snugly against said bushing.

4. The method of forming a bushing structure for metallic barrels and the like consisting of cutting a hole in a supporting wall thereof, forming an outwardly extending collar from the material about said hole and a flange on said collar, fitting an internally threaded body portion in said collar whereby the face thereof rests against said flange, and thereafter forming said collar portion

snugly against the outer side walls of said bushing in a securing relation therewith.

5. The method of forming a bushing structure for metallic barrels and the like consisting of cutting a hole in a supporting wall thereof, forming a polygonally shaped collar from the material about said hole and a flange on said collar, fitting an internally threaded polygonally shaped body portion in said collar whereby the face thereof rests against said flange, and thereafter forming said collar portion snugly against the outer side walls of said bushing in a securing relation therewith. 25

6. The method of forming a bushing structure for metallic barrels and the like consisting of cutting a hole in a supporting wall thereof, forming a collar from the material about said hole and a flange on said collar fitting an internally threaded body portion of a non-circular contour in said collar whereby the face of said body portion rests against said flange, and thereafter forming said collar portion snugly against inwardly converging outer side walls of said bushing 50 whereby a securing means of a dove-tail cross section is obtained. 55

In witness whereof, I have hereunto subscribed my name.

HENRY SCHWARTZ.
